UNITED STATES PATENT OFFICE

124,078

DESIGN FOR A LIGHTING FIXTURE

Edward L. Reeve, Chicago, Ill.

Application January 19, 1940, Serial No. 89,583

Term of patent 7 years

To all whom it may concern:

Be it known that I, Edward L. Reeve, a citizen of the United States of America, residing at Chicago, in the county of Cook and State of Illinois, have invented a new, original, and ornamental Design for Lighting Fixtures, of which the following is a specification; reference being had to the accompanying drawing, forming part thereof.

Fig. 1 is an elevational view of the lighting fixture showing my new design.

Fig. 2 is a section on the line 2—2 of Fig. 1 of the lighting fixture.

I claim:

The ornamental design for a lighting fixture, as shown.
